UNITED STATES PATENT OFFICE.

CHARLES BOOZ, OF BUFFALO, NEW YORK, ASSIGNOR, BY MESNE ASSIGNMENTS, TO GEORGE K. BIRGE, OF SAME PLACE.

DESIGN FOR WALL-PAPER.

SPECIFICATION forming part of **Design No. 24,832**, dated November 5, 1895.

Application filed September 30, 1895. Serial No. 564,218. Term of patent 3½ years.

To all whom it may concern:

Be it known that I, CHARLES BOOZ, a citizen of the United States, residing at Buffalo, in the county of Erie and State of New York, have invented and produced a new and original Design for Wall-Paper, of which the following is a specification, reference being had to the accompanying drawing, showing a part thereof.

The design consists of large center ornaments connected on each side near the base of said ornaments with large scroll-like leaves drooping downward and connecting with large side ornaments. Small scroll-like leaves extend upwardly on the sides of said ornaments, and panel-shaped lines with a row of small balls inside of said lines form the tops of said ornaments, and panel-shaped lines with rows of small balls between said lines

form the bottom of said ornaments, as represented in the accompanying drawing.

The border of the design consists of large ornaments formed of scroll-like leaves and connected panel-shaped lines, with rows of small balls and small panels formed by said lines, with ornamental figures in the center, as shown in the drawing.

What I claim is—

1. The design for wall paper herein shown and described.
2. In the design for wall paper, the border herein shown and described.

Witness my hand this 27th day of September, 1895.

CHARLES BOOZ.
